UNITED STATES PATENT OFFICE.

HORACE E. HENWOOD, OF NEW YORK, N. Y.

ACETYLENE-GAS-GENERATOR-FEEDING MECHANISM.

1,204,016.

Specification of Letters Patent.

Patented Nov. 7, 1916.

Application filed February 1, 1912, Serial No. 674,651. Renewed March 7, 1914. Serial No. 823,247.

To all whom it may concern:

Be it known that I, HORACE E. HENWOOD, a subject of the King of Great Britain, residing at New York city, in the county and State of New York, have invented certain new and useful Improvements in Acetylene-Gas-Generator-Feeding Mechanism, of which the following is a clear, full, and exact description.

- 10 This invention relates to an acetylene gas generator of the general type described in a co-pending application of mine, executed of even date herewith, and originally filed February 1, 1912, Serial No. 674,648.
- 15 The object of this invention is to provide another and specially advantageous type of feeding device for securing substantially absolute uniformity of feed to prevent fluctuations of the light.
- 20 In carrying out my invention, I preferably provide a head for my generator which may be used to fill the same with carbid, and I attach it by means of a flexible diaphragm to the carbid receptacle so as to
- 25 have a vertical movement, its position depending upon the pressure in the chamber, substantially as appears in my said other application. A spindle connected with this head carries a feeding plug at its end, which
- 30 passes through an aperture in the bottom of the carbid receptacle. This feeding plug may be of any proper shape and have any kind of convolutions or projections thereon as may be desired, but to insure an accurate
- 35 feed of the carbid in proper proportion to the consumption of gas and to prevent fluctuation, I provide mechanism to permit this plug to be lowered through the aperture to give a greater or lesser size of opening for
- 40 the feed of the carbid, and at the same time twist and turn the plug to aid in the feed of the carbid.

The scope of my invention will be pointed out in the claims.

- 45 In the accompanying drawings: Figure 1 is a side elevation partly in section of my improved generator. Fig. 2 is a section of the carbid chamber on line 2—2 Fig. 3. Fig. 3 is a section on line 3—3 Fig. 1. Fig. 50 4 is a section on line 4—4 Fig. 2. Fig. 5 is a side elevation of the bushing and helical

sleeve. Fig. 6 is a section on line 6—6 Fig. 2. Fig. 7 is a plan of the filling head with the closure cap removed.

As shown in the drawings, 1 is the water 55 chamber.

2 is the carbid receptacle.

3 is the filling head.

4 are springs tending at all times to hold the filling head inward against the pressure of the gas in the receptacle.

The outlet pipe 5 and the safety valve 6 and gage 7 may be of ordinary construction. The filling head 3 is provided with a closure cap 8 and passages 9, through which carbid may be inserted. The filling head 3 is fastened by means of a diaphragm 10 to an inturned rim 11 of the carbid receptacle 2.

The carbid receptacle has a conical bottom 12 which is also the top of the water chamber 1, through which conical bottom pipes 13 lead the gas to a point near the apex of said conical bottom. A spindle 14 is secured to the filling head 3, so as to rise 70 and fall with it, but to be free for rotation with relation to the filling head, and it is secured to the filling head by a bushing 15 and a threaded pin 16 having a groove 17 therein for engagement by a set screw 18, 80 so that the pin 16 and spindle 14 may rotate freely in the bushing 15, but partake of all vertical movements with it.

The lower end of the spindle 14 carries a conical plug 19 having a cylindrical end 20 fitting an aperture in a bushing 21 secured to the apex of the conical bottom of the carbid receptacle. This bushing 21 carries a sleeve 22 extending into the water chamber and provided with helically disposed strips 25 with open spaces therebetween. The conical plug 19 carries below its cylinder 20 a small diameter plug 23, into the sides of which there project guide pins 24, which also extend through the spaces between the helical strips 25 of the sleeve 22, so that upon a vertical depression of the spindle 14 the plug 19 will be rotated as well as lowered. Of course upon the lowering of the plug 19 the carbid will pass 100 through the spaces between the helical strips above the cylindrical part 20. The plug 19

may be of any shape desired to pass through the opening in the bushing 21. I however, prefer to provide oblique rings thereon forming ribs 26 as will be apparent from 5 examination of Fig. 6.

In carrying out this invention, details of construction may be varied from those shown, and yet the essence of the invention be retained; some parts might be employed 10 without others, and new features thereof might be combined with elements old in the art in diverse ways, although the herein described type is regarded as embodying substantial improvements over such modifications.

As many changes could be made in the above construction, and many apparently widely different embodiments of the invention could be made without departing from 20 the scope thereof, it is intended that all matter contained in the above description or shown in the accompanying drawings shall be interpreted in an illustrative and not in a limiting sense.

It is furthermore desired to be understood 25 that the language used in the following claims is intended to cover all the generic and specific features of the invention herein described, and all statements of the scope of 30 the invention which as a matter of language might be said to fall therebetween.

Subject-matter shown but not claimed herein constitutes the subject-matter of 35 claims in my co-pending applications, Serial Numbers 823,245 and 823,246 filed March 7, 1914. Case Serial Number 823,245 contains claims generic to the disclosures of all three applications, and case Serial Number 823,246, contains claims which are generic 40 with respect to the present application, though specific with reference to case Serial Number 823,245.

I claim as my invention:

1. In an acetylene generator, a water 45 chamber, a carbid receptacle having a feed aperture in its bottom, a flexible diaphragm, a feed plug, a shaft connecting the feed plug with the diaphragm, whereby the feed plug is caused to move up and down in the aperture, and means for imparting a rotary movement to the feed plug in conjunction with its vertical movement.

2. In an acetylene gas generator, a water 55 chamber, a superposed carbid receptacle having a conical bottom provided with a feed aperture, a vertically movable head and a diaphragm connected with the head, a laterally open sleeve with helical guides communicating with the feed aperture, a feed 60 plug in engagement with said helical guides, and a connection between the feed plug and head whereby the plug moves vertically with the head and rotates independently thereof.

3. In an acetylene gas generator, a water

chamber, a superposed carbid receptacle 65 having a conical bottom, a vertically movable head and a diaphragm connecting it with the carbid receptacle, a bushing in the conical bottom of the carbid receptacle and having a feed aperture and a laterally open 70 sleeve with helical guides communicating with said aperture, a feed plug in engagement with said helical guides, and a connection between the feed plug and head whereby the plug moves vertically with the head 75 and rotates independently thereof.

4. In an acetylene generator having a water reservoir and a carbid receptacle provided with a feed aperture, a feed plug, and means for moving said plug vertically and 80 rotatably in the feed aperture, the feed plug having an upwardly tapering portion broken by irregularities.

5. In an acetylene generator, a water reservoir, a carbid receptacle having a central 85 aperture in its bottom, a reciprocating filling head, a means for controlling said head, a flexible diaphragm connecting the reciprocating filling head to the carbid receptacle, a shaft connected to and vertically movable 90 with the reciprocating filling head, said shaft being rotatable independently of said head, a feed plug secured to the lower end of said shaft, said feed plug operating in and controlling the central aperture in the 95 bottom of the carbid receptacle, and a means for imparting a rotary motion to said shaft upon its vertical movement.

6. In an acetylene generator, a water reservoir, a carbid receptacle having a central 100 aperture in its bottom, a reciprocating head, a flexible diaphragm connected with said head, a shaft carried by said reciprocating head, said shaft having a rotary motion upon its vertical movement, a feed plug carried by said shaft having the same vertical and rotary motions as the said shaft and operating through said central aperture in the bottom of the carbid receptacle, and a means for imparting a rotary motion to said 110 shaft upon its vertical movement.

7. In an acetylene generator, carbid feed mechanism comprising a member adapted to move vertically in accordance with the generation of the gas, a feed device movable 115 vertically with said member and rotatable relatively thereto, and means for compelling the rotary movement of said device.

8. In an acetylene generator, the combination of a carbid receptacle having a feed 120 aperture, a water reservoir, and a feed plug vertically movable and rotatable in said aperture.

9. In an acetylene generator having a water reservoir and a carbid receptacle 125 thereover provided with a feed aperture, a feed plug vertically movable in said aperture and comprising a lower closure portion, and

an upwardly tapering feed portion, the said tapering portion being formed with a series of diminishing oblique shoulders.

10. In an acetylene generator having a water reservoir, means for feeding the carbide thereto comprising a carbide receptacle having a feed aperture, and a feed plug vertically movable in said aperture and comprising a lower closure portion and an up-

wardly tapering obliquely ribbed feed por- 10
tion.

Signed at New York city, New York, this 30th day of January, 1912.

HORACE E. HENWOOD.
